UNITED STATES PATENT OFFICE.

JAMES R. LATHAM, OF NEW YORK, N. Y., ASSIGNOR OF ONE-HALF TO
ROBERT MILBANK, OF NEW YORK, N. Y.

NON-REFILLABLE BOTTLE.

SPECIFICATION forming part of Letters Patent No. 727,643, dated May 12, 1903.

Application filed September 13, 1902. Serial No. 123,222. (No model.)

To all whom it may concern:

Be it known that I, JAMES R. LATHAM, a citizen of the United States, and a resident of the borough of Manhattan, in the city and 5 State of New York, have invented a new and useful Non-Refillable Bottle, of which the following is a specification.

My invention relates to non-refillable bottles, and has for its object to provide improved 10 means for automatically locking the valve thereof closed whenever the bottle is in a position to receive liquid therein.

A further object is to provide a device of the above character which will be very simple 15 in construction and which will at the same time lock the valve closed when the bottle is in a vertical position to prevent the opening of the valve by a quick vertical movement of the bottle.

20 A practical embodiment of my invention is represented in the accompanying drawings, in which—

Figure 1 is a vertical central section through the neck of a bottle, showing the position of 25 the parts when the bottle is in a vertical position. Fig. 2 is a similar view showing modified means for supporting the device within the bottle. Fig. 3 is a view similar to Fig. 1, showing the parts in the position which they 30 assume when the bottle is in a horizontal position, and Fig. 4 is a view showing the position which the parts assume when the bottle is in an inverted position.

The body of the bottle is denoted by 1, and 35 its neck comprises a reduced portion 2, adjacent to the body, a reduced mouth portion 3, and an enlarged intermediate portion 4. A guard 5 is provided at the junction of the mouth portion 3 and enlarged portion 4 for 40 preventing any tampering with the non-refillable device, which guard comprises a hollow casing having a plurality of holes 6 through the top thereof and an annular series of holes 7 through the side walls thereof. 45 This guard is held in position by a vertical pivot-rod 8, which supports the several parts of the device.

In the form shown in Figs. 1, 3, and 4 the pivot-rod 8 is secured at its inner end by one

or more spiders 9, carried by a metal tube 10, 50 permanently secured within the reduced portion 2 of the neck of the bottle.

Communication between the interior of the bottle and the exterior thereof is controlled by a float-valve 11, which normally closes the 55 outer end of the tube 10.

In the form shown in Fig. 2 the pivot-rod 8 is supported by arms 9 within the enlarged portion 4 of the neck of the bottle, the ends of the said arms being held between the meeting edges of the upper and lower sections 12 and 13 of the neck of the bottle, which are locked together by a suitable ring 14, permanently secured around the periphery of the enlarged portion 4 over the joint between the 65 said upper and lower sections. In this instance the pivot-rod 8 does not pass entirely through the valve 11.

The means which I have shown for locking the valve closed except when the bottle is in an inverted position is constructed, arranged, and operated as follows: A laterally-extended post 15 is pivoted upon the pivot-rod 8 between a shoulder 16, formed by enlarging the rod, and a shoulder 17, formed by a sleeve 75 permanently secured on the rod. An L-shaped lever is pivoted at the end of one of its arms 18 upon a pintle 19, carried by the free end of the post 15. The other arm 20 of the L-shaped lever projects outwardly from 80 the arm 18 at a point upon the other side of the pivot-bar 8 from the point where the arm 18 is hinged to the said post 15, which outwardly-projecting arm is weighted, as shown at 21. The inwardly-extended arm 22 of the 85 valve-engaging lever is hinged at 23 at the junction of the arms 18 and 20 of the L-shaped lever and the laterally-extended arm of the valve-controlling lever is extended to a point beneath the free end of the post 15. 90 A locking-dog 25 is hinged on the pintle 19 of the post 15, which dog is arranged to swing against the outer face of the lateral arm 24 of the valve-engaging lever when the bottle is in or adjacent to a vertical position. This 95 dog will thus hold the valve closed and prevent its being jumped away from its seat by a violent movement of the bottle when in its

vertical position. The rocking movement of the dog 25 is limited by means of a pin 26, which engages the post 15 when the bottle is inverted.

5 When the bottle is in a substantially horizontal position, the weighted arm 20 of the L-shaped lever will still hold the valve closed, because of the fact that the weight 21 is located at a point tending to swing the arm 18 10 of the L-shaped lever inwardly beyond its center.

The laterally-extended arm 24 of the valve-engaging lever will therefore be pressed by the weighted arm 20 of the L-shaped lever 15 against the back of the valve 11 when the bottle is in its substantially horizontal position.

When the bottle is in an inverted position—as, for instance, that shown in Fig. 4—the L-shaped lever will be swung away from the valve, thereby carrying the valve-retaining lever with it, and thus permitting the valve to fall away from its seat.

The weighted arm 20 of the L-shaped lever 25 is sufficient to hold the post 15 in a vertical position with respect to the pivot-rod 8 whenever the bottle is in other than a vertical position.

What I claim is—

30 1. The combination with the neck of a bottle provided with a passage-way for opening communication between the interior of the neck and the interior of the body of the bottle, of a pivot-rod, a valve having a sliding 35 engagement therewith for closing the said passage-way, means for holding the valve closed when the bottle is in other than an inverted position and means for automatically locking the valve closed when the bottle is in a substantially vertical position.

2. The combination with the neck of a bottle provided with a passage-way for opening communication between the interior of the neck and the interior of the body of the bottle, of a pivot-rod, a laterally-extended post 45 pivoted thereon, a valve having a sliding engagement with the rod for closing the said passage-way, a gravity-controlled device hinged to said post for holding the valve closed when 50 the bottle is in other than an inverted position and a swinging locking-dog hinged to said

post for locking the valve closed when the bottle is in a substantially vertical position.

3. The combination with the neck of a bottle provided with a passage-way for opening 55 communication between the interior of the neck and the interior of the body of the bottle, of a pivot-rod, a valve having a sliding engagement therewith for closing the said passage-way, a laterally-extended post pivoted 60 on the rod, a weighted lever hinged to said post and a valve-engaging lever hinged to said weighted lever for holding the valve closed when the bottle is in other than an inverted position.

4. The combination with the neck of a bottle provided with a passage-way for opening communication between the interior of the neck and the interior of the body of the bottle, of a pivot-rod, a valve having a sliding 70 engagement therewith for closing said passage-way, a laterally-extended post pivoted on the said rod, a weighted lever hinged to said post, a valve-engaging lever hinged to said weighted lever, in position to hold the 75 valve closed when the bottle is in other than an inverted position and a gravity-controlled locking-dog hinged to said post for locking the valve closed when the bottle is in a substantially vertical position.

5. The combination with a bottle having a neck comprising two reduced portions and an intermediate enlarged portion, of a non-re- 85 fillable device therefor comprising a pivot-rod, means for supporting it within the neck 90 of the bottle, a guard carried thereby adjacent to the mouth of the bottle, a valve having a sliding engagement with the rod for closing communication between the interior of the bottle and the exterior thereof and a gravity-controlled device carried by the rod for holding the valve closed when the bottle is in other than an inverted position.

In testimony that I claim the foregoing as my invention I have signed my name, in presence of two witnesses, this 10th day of September, 1902.

JAMES R. LATHAM.
